United States Patent Office

Des. 176,728
Patented Jan. 24, 1956

176,728

BOTTLE

Barry V. Nolan, Chicago, Ill., assignor to Bluhill Foods,
Inc., Denver, Colo., a corporation of Colorado

Application April 25, 1955, Serial No. 35,658

Term of patent 14 years

(Cl. D58—8)

Fig 1

Fig 2

Fig. 1 is a top plan view of a bottle, showing my new design; and

Fig. 2 is a front elevational view thereof.

The sides of the bottle not shown are the same as the side shown.

I claim:

The ornamental design for a bottle, as shown and described.
